**BRIDGE SUPPORT FOR LOAD SUPPORTING
LATHS IN VERTICAL STORAGE FILING
CABINET**

1 Claim. (Cl. 129—16.7)

This invention relates to load supporting laths in vertical storage filing cabinets in which the laths move along guide rails or the like and from which drawings, maps, and the like may be suspended.

Drawings and other large sheets have heretofore been stored vertically in filing cabinets by being suspended on pins projecting horizontally from metal laths, the pins fitting through holes spaced along the margin of each sheet. Wherever such load carrying laths are used, however, they are subject to bending between their supported ends when extreme loading is applied between these ends. The bending of laths due to heavy loading not only renders the filing cabinets difficult to manipulate but also tends to misalign the pins with the margin holes, with resultant danger of damaging the drawings.

It is therefore the prime object of the present invention to provide means for maintaining such laths straight and horizontal under varying load conditions without substantially increasing the weight of such lath or interfering with its effective functioning in the filing cabinet.

In general, the invention is featured by the provision of a re-enforcing member connected between the ends of a metal lath of the type described over a bridging member bearing on the underside of the lath. In a preferred embodiment of the invention, the re-enforcing member comprises a flexible, endless wire cable looped through apertures in the ends of the lath and accommodated in the outer end of the bridging member which is preferably adjustable as to height.

Other objects, features and advantages of the invention will be apparent to those skilled in the art from the following detailed description of a preferred embodiment thereof together with the accompanying drawings in which:

FIG. 1 is a plan view of a vertical storage filing cabinet having load supporting laths employing the invention;

FIG. 2 is an elevation on an enlarged scale of one of the laths showing the novel bridging and re-enforcing members;

FIG. 3 is an enlarged, fragmentary, partially sectional view on line 3—3 of FIG. 2 of the bridging member which cooperates with the re-enforcing member;

FIG. 4 is an enlarged sectional view along the line 4—4 of FIG. 2; and

FIG. 5 is an enlarged sectional view on line 5—5 of FIG. 2.

With reference now to the drawings, and particularly FIG. 1 thereof, a vertical storage filing cabinet 10 is provided with a plurality of laths 20 movable on bearings 12 in tracks 14 in the cabinet. Shaft 15 connected sprockets 16 and chain members 18 maintain the parallel relationship of the laths 20 as they are moved. Interspersed pins 22, 24 of facing portions of the laths 20 are provided to support stored materials.

Each movable lath 20, one of which is shown in FIG. 2, has bearing on the center underside thereof a bridging member 25 comprising a lug 26 which has a radial bore 28 therethrough adapted to accommodate and support the rotatable shaft 15 carrying the sprockets associated with the lath.

A screw-threaded spindle 30, FIG. 3, fitted with a locking nut 32 is located in a complementary axially extending

2

threaded hole 34 in the lug 26 to project further downwardly and transversely of the lath. A boss 36 having parallel, horizontal slots 38, 40 therein spaced apart substantially the thickness of the lath is secured in a freely rotatable manner on the end of the spindle 30. By rotation of the spindle 30, the free end thereof at boss 36 can be extended more or less as desired from the underside of the lath 20 and the locking nut 32 will be used to secure the spindle 30 in the desired position. Radial bore 31 in spindle 30 is provided to permit insertion of a key for turning and adjusting the spindle 30.

Adjacent each end of the lath 20 a hole 42, 44 is made, preferably adjacent the underside of the lath 20, through the thickness of the lath 20 through which a length of strong, light, non-extensible, flexible wire cable 46 may be threaded. A locking grub screw 48 is threaded through the lath 20 to intersect one of the holes 42 for the cable 46 so that the cable 46 may be easily secured, as in FIG. 4, as an endless loop extending between the underside of the lath 20.

The mid-portions of the loop are located in the slots 38, 40 through the boss 36 on the end of the screw-threaded spindle 30, and it will be understood that by varying the length of the spindle, the cable will exert a force on the lath which will tend to bow the lath upwardly. It will be further understood that this bowing action can be utilized to counteract a downward bowing action of the lath due to loading of the pins supporting the drawings.

In operation, after the lath is loaded, spindle 30 is rotated for lengthening until the lath 20 is straight. The spindle 30 is then locked in position by locking nut 32. If the load is materially changed at a later time, locking nut 32 may be released, the spindle 30 appropriately adjusted, and nut 32 locked once again. If desired, prior to initial loading, a prestress may be placed on the lath 20 by lengthening spindle 30 to anticipate the load factor and final adjustment of the spindle 30 may then be made after loading.

In practice it has been found that the use of laths as above described has enabled even very severely overloaded cabinets to operate smoothly and easily without any damage to drawings filed therein, since the laths and alignment of supporting pins may be kept horizontal.

Other embodiments of this invention will occur to those skilled in the art which are within the spirit and scope of the following claim:

What is claimed is:

In a vertical storage filing cabinet, a load carrying lath having means at its ends for support thereof, and a plurality of horizontally extending loading pins projecting from a vertical side of said lath, that improvement which comprises:

a bridging member positioned centrally of said lath bearing on the underside thereof, and having a free end spaced vertically from the central portion of said lath;

said lath having a hole at each end extending horizontally therethrough;

a flexible cable threaded through one hole and having its ends secured in the other hole thereby providing an endless loop extending tautly over said bridging member;

said bridging member comprising a lug bearing on said lath having a vertical threaded opening therein;

a threaded spindle in said threaded opening;

a boss rotatably mounted on the end of said spindle remote from said lug over which said flexible cable extends;

said boss having a pair of horizontal channels thereacross spaced substantially the width of said lath;

said looped cable being positioned in said channels;

means for rotating said spindle to adjust the tension
on said cable; and
a locking nut being provided on said spindle;
whereby load applied to said lath at the center thereof
may be distributed to the ends thereof.
